UNITED STATES PATENT OFFICE.

GUSTAVE WENZELMANN, OF GALESBURG, ILLINOIS.

SILO.

1,116,654.

Specification of Letters Patent. Patented Nov. 10, 1914.

Application filed June 2, 1913. Serial No. 771,329.

To all whom it may concern:

Be it known that I, GUSTAVE WENZELMANN, a citizen of the United States, and a resident of Galesburg, in the county of Knox 5 and State of Illinois, have invented a new and useful Silo, of which the following is a specification.

My invention relates to silos and similar circular or polygonal-sided structures.

10 One of the main objects of the invention is to provide novel means for automatically retaining in proper stress the several individual sections of which the silo shown is composed, which sections are prone to contract and expand accordingly with varying 15 seasons and weather conditions. It is to be understood, however, that this feature of my invention is not limited to its embodiment in an independent-section silo, but that 20 it is applicable to structures having a continuity of united sections.

Another object is to provide novel sections and intermediate means, as standards or columns, whereby such structures may be 25 well and durably erected, even by one unskilled in the arts of carpentry and joinery, and whereby an injured or broken and therefore useless piece may be removed and another readily substituted.

30 Another object is to avoid overlapping the ends of the horizontally laid strips, thus saving a relatively large expense which attaches to cutting off the ends of the strips at carefully predetermined angles.

35 Still another object is to provide a construction in which the doorways may be conveniently arranged and in which ready placement of a door or doors may be made in any section.

40 A further object is to provide a wall which will eliminate danger of the ensilage freezing except it be subjected to extraordinary cold temperatures.

45 A special object is to construct each vertical section entirely independent of another or others, and independent also of the vertically arranged elements intermediate them.

Another object is to generally improve the construction of structures of this character.

50 Minor objects will be in part obvious and in part specifically mentioned.

In the accompanying drawings, which constitute a part of this specification: Figure 1 is a fragmental top-plan of a silo, showing 55 the binding means and showing also the manner of assembling the vertical sections

and standards; Fig. 2, an elevation of the upper portion of a silo embodying the elements shown in Fig. 1; Fig. 3, an enlarged detail—a side elevation; Fig. 4, a transverse section, enlarged, showing modified forms of horizontally laid section-strips, the illustrations being of hollow brick or tile; Fig. 5, a similar view, showing a preferred method of uniting wooden strips; Fig. 6, a modification, an enlarged, fragmental, transverse section, showing a sectional hollow wall; Fig. 7, a detail modification, showing another form of hollow block construction and assemblage; and Fig. 8, an elevation of the structure shown in Fig. 7.

Considering said drawings in detail and referring to the several parts thereof by distinguishing reference characters, the same one of which is uniformly employed to designate the same part in the different views, 2, 2, designate standards, each of which is wedge-shaped in cross section and coextensive with the silo wall in height, but which may be made up of several short pieces if preferred.

3—3 designate section-strips which in Fig. 5 are shown as constructed of horizontally laid lengths of wood, as "two by fours," the upper edges or corners of which are shown as rounded off. The ends of the strips 3 are preferably sawed at right angles to their longitudinal lines, or square, so that when abutted against one of the beveled sides of a standard 2 its length will be at an obtuse angle to the front face thereof, in order that a multi-sided polygonal structure may be laid without careful measurements. The number of sides and angles will be dependent upon the degree of angularity of the standards. When the strips 3 are of wood I prefer that they be united as shown in Fig. 5, and when of clay or cement, mortar 4 or the like is employed.

When the standards 2 and independent 100 vertical sections 5—each of which may be constructed of any suitable number of superposed strips 3—have been erected to a suitable height, each pair thereof is bound or united by an inner binding-plate 6, an outer 105 binding plate 7, an adjusting iron 8, and a binding hoop 9. Of each of these elements any desired and suitable number may be employed. Each plate 6 is preferably a long strip of suitable material which is secured 110 by lag screws 20 to the inner face of a standard 2, its sides overlapping the adjacent ends

of the strips 3. However, if it be desired, the ends of the strips 3 may be rabbeted on their inner faces, and the sides of the plates 6 laid into the recesses thus provided, in which event the plates will be flush with the inner faces of the strips and a smooth interior will result. These plates may be made up of a plurality of short strips if preferred.

Each plate 7 is preferably a strip of suitable material the inner face of which is shaped to conform to the outer face of the standard 2 and the adjacent portions of the strips 3. It is so evident that this plate also may be made in sections that I have not deemed it necessary to encumber the drawings with illustrations of this and other obvious modifications.

Each adjusting iron 8 comprises a base 10 tapered outwardly from top to bottom, to form an inclined plane, and at each end of the arm 11 is a shoulder or abutment, 12, 12', for purposes presently described. A circle described around the silo and taken at the upper portions of an annular series of irons 8 will be perceptibly less in diameter than one similarly described around the lower portions of the inclined planes. Lag screws or other suitable means secure the irons to the plates 7, but said irons may be otherwise suitably secured thereto, or to other elements which will retain them in position, if preferred. The particular character of the hoop 9 to be employed is unimportant. The one illustrated is circular in cross section and provided with threaded ends which engage the threads of an ordinary turnbuckle 14.

25, 25 indicate openings for suitable doors, not shown.

40 In the modified wall structure shown by Fig. 6 I employ horizontally laid spaced strips 3 each having rabbeted ends 15. Each rabbet receives one edge of a side-wall strip, the outer wall strips being indicated by 16 and the inner ones 17. Both toe-nailing and straight nailing may be resorted to, to rigidly unite the parts of a structure thus constructed, and inasmuch as mill ends, "shorts" and other inexpensive lumber may be used, and all the work being of a rough character requiring neither careful measurements nor hand sawing, an efficient and durable silo may be erected at a minimum cost.

55 One great advantage of a silo or other similar exposed structure made from flat-wise or horizontally laid strips of wood is that there is but very little longitudinal expansion or contraction, due to either heat or cold, moisture or dryness, and consequently a minimum of contraction or expansion of the building. There will therefore be but little movement of the hoops 9 after they are once adjusted by means of the several turnbuckles. However, should a ma-

terial or unusual contraction of the silo occur, transversely thereof, the gravity of the hoops will cause them to slide downwardly on the inclined plane 11 to automatically tighten them; and should the contrary condition arise and the silo expand or "swell" abnormally with relation to the degree of expansion of the hoops, the latter will, by reason of the great force exerted by the structure in so expanding, travel in the path of least resistance, which is upwardly on said inclined plane, to again automatically adjust themselves to the changed dimension of the silo. The abutments 12 and 12' limit the movement of the hoop 9 in an evident manner.

In Figs. 7 and 8 I have shown hollow silo-wall-blocks 21 of concrete or tile. Each of these comprises side walls 22, and a top 24 having one or more openings 26. As in the case of the strips, these tiles are superposed, the lower edges of the side and end walls resting on the top of the block immediately below, which top is preferably convex in order that the sealing material poured through the opening 26 in the block above will flow in all directions to make a continuous joint. To replace a useless strip or unit of either of the vertical sections 5 it may be knocked out and the securing means (as the nails or the cement) removed. The upper strips may then be driven or otherwise forced downwardly to fill the gap, whereupon a new strip may be laid in between two standards 2 and on top of the upper strip of the section being repaired, whereupon it may be secured in the usual manner. Because of the square ends of the horizontally laid strips there will be but a minimum of waste material. Should it be desired, each section may be built as a unit before being erected. Should the structure blow over, as sometimes occurs, the individual sections 5 will fall free from each other and the uninjured ones be again used, while usable portions of those which are partly destroyed may be again utilized. In moving the structure from place to place the value of this feature will be appreciated, as every unit portion of the structure may be separated from the others and not only easily transported but readily reassembled.

In the modification shown in Figs. 7 and 8 I have illustrated one which is not only impervious to water but which will prevent freezing of the contents of the silo except in an extremely cold temperature and where the structure is entirely exposed. It will be observed that it is composed of a plurality of units, superposed, and that it may be laid with the edges of the units abutting the edges of the standards 2 and the units secured in place by the binding plates 6 and 7.

Many of the details and combinations illustrated and herein described are not es- 130

5 essential to the invention, broadly considered. All this will be indicated in the claims hereof, wherein the omission of an element or the non-inclusion of reference to the detail features of the elements is intended to be a formal declaration of the fact that the omitted elements or features are not essential to the invention covered by that claim.

10 Having thus described the nature of my invention, and having stated its objects, purposes and advantages, I claim as new and desire to secure by Letters Patent the following, to-wit:—

15 1. A silo comprising a plurality of independent sections each of which is composed of horizontally laid strips, a wedge-shaped element interposed between each pair of sections, and means for uniting said sections and wedge-shaped elements.

20 2. A silo comprising a plurality of independent sections each of which is composed of horizontally laid strips, the sides and ends of which are at right angles to each other, a wedge-shaped element interposed between each pair of sections, a hoop for binding said sections and wedge-shaped elements, and means for manually tensioning said hoop.

25 3. A silo comprising a plurality of independent sections each of which is composed of flatwise laid strips, a wedge-shaped element between the adjacent ends of each pair of sections, a binder secured at the inner

30 face of each of said wedge-shaped elements and adapted to retain the adjacent edges of the contiguous sections, and a binder similarly disposed on the outer face of each wedge-shaped element and adapted to retain the adjacent edges of the contiguous sections.

35 4. A silo comprising a plurality of independent sections each of which is composed of horizontally laid strips, a wedge-shaped element between each pair of sections, a binder on the inner face of said wedge, means for securing it, a binder on the outer face of the wedge, and means whereby said sections, wedges and outer binder are held from separation.

40 5. A silo comprising a plurality of independent sections each of which is composed of horizontally laid strips, a wedge-shaped element between each pair of sections, a binder on the inner face of said wedge, means for securing it, a binder on the outer face of the wedge, means whereby said sections, wedges and outer binder are held from separation, and means for tensioning the last recited element.

45 In testimony whereof I hereunto sign my name, this 27th day of May, 1913, in presence of two subscribing witnesses.

50 GUSTAVE WENZELMANN.
